US00D883651S

(12) **United States Design Patent** (10) **Patent No.:** **US D883,651 S**
Harmon et al. (45) **Date of Patent:** **** May 12, 2020**

(54) **JOINT STABILIZATION SOCK**

- (71) Applicant: **Better Walk, Inc.**, Atlanta, GA (US)
(72) Inventors: **Tyler Jack Prescott Harmon**, Decatur, GA (US); **Partha Sarathy Unnava**, Atlanta, GA (US); **Pranav Chunduri**, Cary, NC (US)
(73) Assignee: **BETTER WALK, INC.**, Atlanta, GA (US)

(**) Term: **15 Years**

(21) Appl. No.: **29/631,819**

(22) Filed: **Jan. 3, 2018**

(51) **LOC (12) Cl.** 02-04

(52) **U.S. Cl.**

USPC **D2/980**; D24/192

(57) **CLAIM**

The ornamental design for a joint stabilization sock, as shown and described.

DESCRIPTION

FIG. 1 is a perspective view of an exemplary joint stabilization sock;

FIG. 2 is a front view of an exemplary joint stabilization sock;

FIG. 3 is a rear view of an exemplary joint stabilization sock; FIG. 4 is a right side view of an exemplary joint stabilization sock;

FIG. 5 is a left side view of an exemplary joint stabilization sock;

FIG. 6 is a top view of an exemplary joint stabilization sock; and,

FIG. 7 is a bottom view of an exemplary joint stabilization sock.

The broken lines in the drawings are for the purpose of illustrating environmental structure and form no part of the claimed design.

1 Claim, 7 Drawing Sheets
